Letters Patent No. 652. Dated May 23d. 1854.

The schedule referred to in these Letters Patent, & making part of the same.

To all whom these presents shall come:

Be it known that we, Jacob Beesley & Edward J. Delany, of Philadelphia, in the County of Philadelphia, & State of Pennsylvania, have invented a new design for stoves, & that the following is a full, clear, and exact description of the principle or character which distinguishes it from all other things before known, & of the usual manner of making modifications using the same, reference being had to the accompanying drawings.

Fig. 1 is a side view illustrating the oven and fire doors.

Fig. 2 is a view of the back plate.

Fig. 3 is a front view of the front plate & front door.

These drawings illustrate our design for the Golden Star Cooking Stove, other parts of the stove being plain and ornamental at pleasure.

What we claim as our invention is the design for
